UNITED STATES PATENT OFFICE.

ALEXANDER HEMSLEY, OF LANSDOWNE, PENNSYLVANIA.

FLASH-LIGHT APPARATUS.

SPECIFICATION forming part of Letters Patent No. 699,522, dated May 6, 1902.

Application filed July 25, 1901. Serial No. 69,640. (No model.)

To all whom it may concern:

Be it known that I, ALEXANDER HEMSLEY, a citizen of the United States, residing at Lansdowne, in the county of Delaware and State of Pennsylvania, have invented certain new and useful Improvements in Flash-Light Apparatus, of which the following is a specification.

My invention has relation to an apparatus for igniting flash-light powder; and in such connection it relates to the construction and arrangement of such an apparatus.

The main requirements of a flash-light apparatus are that the flash-light powder shall be ignited at the required instant and that premature explosion or accidental ignition of the powder shall be prevented. To provide such an apparatus is the principal object of my present invention.

The nature and scope of my said invention will be more fully understood from the following description, taken in connection with the accompanying drawings, forming part hereof, in which—

Figure 1 is a top or plan view of a flash-light apparatus embodying main features of my invention. Fig. 2 is a longitudinal central sectional view of the same; and Fig. 3 is a transverse sectional view on the line xx of Fig. 1, showing a flashing powder in the receptacle of the apparatus and with igniting means for the powder embedded therein.

Referring to the drawings, A represents a rectangular or other-shape block provided with a powder-receptacle a' .

b and b' are metal arms each pivotally attached, as at b^3 , to the block A and each slotted, as at b^2 , to removably retain a wire c , adapted to bridge the two arms b and b' .

These two arms b and b' have free ends b^4 projecting above the face of the block A and adapted to engage the terminals of a battery or other electric circuit, in which is included a circuit-making switch device d , adapted to

be brought into contact with a contact-point d' to establish the circuit through the apparatus with the battery. The current from the battery B passes by the line 10 through the circuit-making switch device d , contact-

point d' , line 11, the terminal of said line consisting of a snap-spring e , adapted to fit snugly the projecting end b^4 of the metal arm b , through the metal arm b , inserted wire c ,

bridging the respective arms b and b' by the metallic arm b' ; split terminal e' , and line 12 back to the battery B. The powder or similar material to be exploded or ignited is mounted in the receptacle a' , so as to envelop or bring the wire c , bridging the respective metal arms b and b' , within the body of the mass or mound of powder or the like in the receptacle a' of the block A, when by manipulation by hand of the circuit-making switch device d to cause the same to contact with the contact-point d' the current will then pass from the battery B through the respective lines and the wire bridging the metal arms b and b' to heat the wire up sufficiently embedded in the mass or mound of powder placed in the receptacle a' , as clearly illustrated in Fig. 3, to cause an instant explosion or ignition of said powder, and thereby to produce the desired intense flash-light for instantaneous photography or other purposes.

By pivotally attaching the arms b and b' , as well as slitting their ends b^2 , two means of varying the bridging resistance c are provided. Thus the wire c may be removed and replaced from the split ends by a wire of varying thickness, or the arms b and b' may be turned on the pivots b^3 to vary the length of the wire c , bridging said arms.

Having thus described the nature and object of my invention, what I claim as new, and desire to secure by Letters Patent, is—

In a flash-light apparatus, a block provided with a receptacle for the powder, two metallic arms pivotally attached to said block and each having a split end extending over the receptacle, a resistance inserted in said split ends to bridge the arms, and said arms having a projecting free end extending above the face of the block to receive the terminals of an electric circuit, all arranged so that variations in the bridging resistance may be obtained either by removing and replacing the resistance in the split ends of said arms or by turning the arms on their pivotal supports.

In testimony whereof I have hereunto set my signature in the presence of two subscribing witnesses.

ALEXANDER HEMSLEY.
